INVENTOR:

S. Gayle Woodruff.

United States Patent Office.

S. SAYRE WOODRUFF, OF BROOKLYN, NEW YORK.

Letters Patent No. 64,822, dated May 14, 1867.

IMPROVEMENT IN BABY-CARRIAGES.

The Schedule referred to in these Letters Patent and making part of the same.

TO ALL WHOM IT MAY CONCERN:

Be it known that I, S. SAYRE WOODRUFF, of Brooklyn, in the county of Kings, and State of New York, have invented certain new and useful Improvements in Baby-Carriages; and I do hereby declare that the following is a full, clear, and exact description of the same, reference being had to the accompanying drawings, making a portion of this specification, in which—

Figure 1 is a side view of a baby-carriage constructed according to my invention.

Figure 2 is a plan view of the same.

Similar letters of reference indicate corresponding parts in both figures.

This invention consists in a reversible pivoted tongue, so combined with the body of a suitable carriage that the said carriage, when in use, may be either drawn or pushed along, as may be desired, with equal convenience and facility. The invention further consists in the combination of a tongue of this description constructed with elastic sides, in combination with lugs or stops formed upon the body of the carriage, whereby such tongue may be very easily and effectually secured in either a forward or rearward position upon the carriage, as may be required.

To enable others to understand the nature and construction of my invention, I will proceed to describe it with reference to the drawings.

The body of the carriage is represented at A, and is supported upon the two main wheels B, and furnished, when preferred, with a caster-wheel, a, at its forward end. The tongue or shaft, by which the carriage is drawn or pushed along, as the case may be, is marked C, and has the lower ends of its two side portions a* pivoted to the opposite sides of the body A, near the bottom thereof, in any suitable manner, or, if desired, the said tongue may be pivoted directly upon the axle c of the main or supporting wheels B. The said tongue being thus pivoted may be turned into a forward position, as shown in black in the drawings, so as to permit the carriage to be drawn thereby when desired, or may be turned back into the position shown in red outline in fig. 1, which being done, the carriage may be pushed along by means of the said tongue, instead of being drawn, as just mentioned. In order to provide for the proper retention of the tongue C in either position, when the carriage is in use, there is secured upon each side of the rear part of the body A an ear or stop, d, which has formed in it a notch, a'. Secured in like manner to the forward part of the body A, one upon each side thereof, are two similar ears or stops e, which, like the ears d, are formed with notches, also marked a'. These ears d e have their surfaces made sloping or inclined, as shown more fully in fig. 2, in order to facilitate the passing of the elastic sides a* of the tongue C over or upon the said ears, as presently explained. The two side portions a* of the tongue C are made sufficiently elastic to be capable of yielding slightly in a lateral direction, so that when the tongue is turned forward, as hereinbefore set forth, the said sides will pass over or upon the ears e and enter the notches a' thereof, and be held in position thereby as required in drawing the carriage, and so that when the tongue is turned back, as shown in red outline in fig. 1, and also hereinbefore explained, the said sides will, in a similar manner, catch in the notches a' of the ears d and hold the tongue in such rearward position as required in pushing instead of drawing the carriage.

By making the tongue reversible in this manner the carriage may be very readily converted from one capable of being drawn into one capable of being pushed along, and the means just described render the retention of the tongue in either position as firm and secure as if the said tongue were permanently attached in such position to the carriage.

What I claim as my invention, and desire to secure by Letters Patent, is—

1. The combination of the pivoted reversible tongue or shafts with the body of the carriage, substantially as herein set forth for the purpose specified.
2. The combination of the pivoted reversible tongue or shafts constructed with elastic sides, as set forth, with the ears or stops d and e formed upon the body of the carriage, substantially as and for the purpose specified

S. SAYRE WOODRUFF.
